UNITED STATES PATENT OFFICE.

JOHN J. SCHILLINGER, OF NEW YORK, N. Y.

CONCRETE PAVEMENT.

SPECIFICATION forming part of Letters Patent No. 247,421, dated September 20, 1881.

Application filed May 11, 1881. (No model.)

To all whom it may concern:

Be it known that I, JOHN J. SCHILLINGER, a citizen of the United States, residing at New York, in the county of New York and State 5 of New York, have invented new and useful Improvements in Concrete Pavements, of which the following is a specification.

This invention relates to an improvement on the invention described in my Patent No. 10 105,599, reissued May 2, 1871, No. 4,364.

My present invention consists in a concrete pavement composed of roof-shaped or pyramidal sections formed on the ground.

This invention is illustrated in the accompanying drawings, in which—

Figure 1 represents a transverse section of my pavement. Fig. 2 is a perspective view of one of the roof-shaped blocks. Fig. 3 is a similar view of one of the pyramidal blocks.

20 Similar letters indicate corresponding parts.

The concrete pavement described in my Re-issue Patent No. 4,364 consists of sections which are formed successively by spreading the concrete mass, while in a plastic state, on 25 the foundation or bed of the pavement, either in molds or between movable joists of the proper thickness, the formation of the second section or block being commenced after the first section or block has set, so that the edges of 30 the several blocks do not adhere to those of the adjoining blocks, and that when the pavement is complete each block or section is allowed to heave separately from the effect of frost or to be raised or removed separately 35 whenever occasion may arise, without injury to the adjacent blocks.

Heretofore the blocks or sections formed in the manner above stated have been of uniform thickness throughout, and I have found that 40 such blocks, particularly if made of large size, have been liable to crack. For instance, if in laying a sidewalk according to the method described in my reissued patent above named the blocks are made of sufficient length to extend 45 from the curb to the building on the inner side of the sidewalk, they are liable to crack

in such a manner that they have to be relaid very frequently. This defect I have sought to overcome by my present invention by forming roof-shaped blocks A instead of blocks of uniform thickness throughout. 50

In forming a sidewalk according to this invention, I prepare the bed B in the manner shown in Fig. 1, and then I place two joists from the curbstone C to the building D at a 55 suitable distance apart upon the bed, and the space between these joists is then filled up with the plastic mass. After the first block has been completed and set the joist situated on one of its edges is removed a sufficient distance to form the second block, and so on. 60

A roof-shaped block formed in this manner can be made with safety ten feet long and four feet wide, and it is not liable to crack by the influence of frost or otherwise. 65

Instead of making the block roof-shaped, as shown in Figs. 1 and 2, they can be made pyramidal, as shown in Fig. 3. The concrete which I use by preference in forming my blocks consists of cement, sand, and gravel, which are 70 mixed together with water in suitable proportion to form a plastic mass.

My blocks have also the great advantage that the same, when placed on an incline, are not liable to become displaced by the action of 75 gravity.

What I claim as new, and desire to secure by Letters Patent, is—

A concrete pavement laid in detached sections directly upon the ground or bed, and each 80 section formed of plastic material into a roof-shape or pyramidal outline, which rests throughout its breadth on the ground or bed, substantially as shown and described.

In testimony whereof I have hereunto set my 85 hand and seal in the presence of two subscribing witnesses.

JOHN J. SCHILLINGER. [L. S.]
